Louis O. French

ATTORNEY.

UNITED STATES PATENT OFFICE.

MARTIN CHRISTENSEN, OF ELMHURST, ILLINOIS, ASSIGNOR TO THE CHRISTENSEN MACHINE COMPANY, OF RACINE, WISCONSIN, A CORPORATION OF WISCONSIN.

SIGNATURE-HANDLING APPARATUS.

Application filed January 2, 1926. Serial No. 78,930.

The invention relates to signature-handling apparatus.

In the making of pamphlets, magazines, and other bound forms of groups of signatures, hereinafter called books, it is sometimes desired to have the cover page overlap the main body or group of signatures of the book, and the object of this invention is to provide an apparatus for accomplishing this result, and more particularly one which may be used with a saddle-stitch type of book-stitching machine.

The invention further consists in the several features hereinafter set forth and more particularly defined by claims at the conclusion hereof.

In the drawings, Fig. 1 is a side elevation view of apparatus embodying the invention, parts being broken away;

Fig. 2 is a vertical sectional view taken on the line 2—2 of Fig. 1;

Fig. 3 is a detail plan view of the feed finger;

Fig. 4 is a detail elevation view of the feed finger.

The apparatus includes the main signature-conveying mechanism and means or auxiliary conveyor mechanism for moving the body or main group of signatures faster than the cover page so that the cover is caused to overlap the main group of signatures when these signatures and cover page are presented to the stitching mechanism.

The main signature-conveying mechanism may be of any suitable form. The form shown is that of my prior United States Patent No. 1,297,322, of March 18, 1919, wherein the conveyor is of the endless type, including a plurality of saddle members 5 having depending spaced-apart flanges 6 with links 7 pivotally secured within said flanges and links 8 pivotally secured without said flanges and to said links 7 by pins 9. The upper run of the conveyor is shown as 45 guided by a straight bar 10 disposed between the flanges 6 and over which the links 7 run, said bar being carried by the framework 11 of the machine. This conveyor runs over sprockets 12 at the upper 50 and lower ends of the framework at both ends of this apparatus, one of the sprockets 12 being mounted on a frame 13 secured to the main frame by a bolt 14, the particular framework being shown in my prior United

States Patent No. 1,140,734, of May 25, 1915. 55 The conveyor may also take the form of my prior United States Patent No. 937,925, of October 26, 1909, in which a stationary inverted V-shaped saddle has a longitudinally-extending slot therein through which pins 60 carried by an endless chain project to move the signatures along the saddle. As shown, the signature-engaging pins 15 are secured at spaced intervals to the saddle members 5 and carry a group of signatures 16 along 65 the saddle.

The auxiliary conveying means is here shown as including a reciprocating bar 16 which is suitably guided in the frame and is moved by a cam 17 at a faster rate than 70 the main conveyor during its forward feeding stroke. This cam 17, driven by a rotary shaft 18, engages a roller 19 on a lever 20 pivoted at 21 to the frame and operatively connected by a link 22 with the bar 16, the 75 roller 19 being held against the cam 17 by a tension spring 23 secured at one end to said lever and at the other end to the frame. The bar 16 is provided with a plurality of spaced tapped holes 24, any one of which 80 may receive a clamping-screw 25 which adjustably secures the finger device 26 to said bar.

This finger device includes an angled base or supporting member 28 having a longitudinally-extending slot 29 through which the screw 25 passes. A signature-engaging finger 30 is pivotally mounted on the top of the member 28 by a pivot screw 31 and is normally urged outwardly by a spring 85 32; is limited in its movement by a screw 33 on the member 28 working in a slot 34 in said finger; has a straight face 35 for engaging the edges of a group of signatures, and a tapered or inclined face 36 to facilitate its return movement past a group of signatures. The cam shaft 18 is designed to revolve once during the time the main conveyor chain moves a distance equal to the space between the pins 15 on the conveyor, 90 and this moves the finger device 26 at a faster rate than the conveyor, with the result that the main group of signatures engaged by the finger 30 are moved ahead of the cover page 31 superimposed upon them 95 but not engaged by said finger so that when the signatures are delivered from this apparatus to the stitcher feed mechanism, one 100 105

edge, or both edges, of the cover page will overlap the main body of the signatures forming the book.

To facilitate the action of the finger, a 5 guardplate 37 is secured to the bar 10 and keeps the depending portions of the signatures on that side of the machine in line with the face 35 of the finger 30, and to prevent interference with the cover page a 10 bar 38, extending lengthwise of the conveyor for about one-half the length thereof and supported by frame members 39 from the frame of the machine, forms a rest for the depending portion of the cover page 15 on the side adjacent the finger 30.

With this construction the main body of the book is placed directly on the saddle and the cover page is placed on this group of signatures and astride the bar 38 and then 20 as the signatures thus assembled travel along the saddle they are operated upon as previously described to move relative to the cover page.

After the bar 16 has made its forward 25 stroke it is returned for the finger 30 to displace the next group of signatures relative to the cover page, and the inclined face 36 together with the spring 32 permits the finger to move back under the advancing main 30 group of signatures until it passes their rear edges and then moves into abutting engagement with said edges and advances them relative to the cover page, as previously described.

As the finger device 26 is adjustably mounted on said bar 16, books of various sizes may be readily handled on the machine.

I desire it to be understood that this invention is not to be limited to any particular form or arrangement of parts except in 40 so far as such limitations are expressed in the claims or necessitated by the prior art.

What I claim as my invention is:

1. The combination, with the main signature-conveying mechanism, of auxiliary conveyor mechanism for advancing the signatures forming the inside of the book at a faster rate than the cover page during their movement with the main conveying mechanism to overlap said cover page relative to 50 said inside signatures.

2. The combination, with the saddle-conveyor mechanism of a saddle-stitch book-

stitching machine, of an auxiliary conveyor mechanism cooperating with said main conveyor mechanism to produce a relative displacement of the signatures forming the inside of the book relative to the cover page to present the group of signatures to the stitching mechanism with the cover page 60 overlapping the inside signatures. 55

3. The combination, with the main signature-conveying mechanism, of an auxiliary conveyor mechanism comprising a reciprocating member and a finger mounted on said member and engageable with the signatures forming the inside of the book to advance them relative to the superimposed cover page to overlap said cover page relative to 70 said inside signatures. 65

4. The combination, with the main signature-conveying mechanism, of an auxiliary signature-feed mechanism including a reciprocating finger engageable with the signatures forming the inside of the book to 75 advance them relative to the superimposed cover page to overlap said cover page relative to said inside signatures, and means for holding said cover page away from said finger. 80

5. The combination, with the main signature-conveying mechanism, of an auxiliary signature-feed mechanism comprising a reciprocating member and a finger adjustably mounted on said member and engageable 85 with the signatures forming the inside of the book to advance them relative to the superimposed cover page to overlap said cover page relative to said inside signatures. 80

6. The combination, with the main signature-conveying mechanism of a saddle-stitch book-stitching machine, of an auxiliary signature-feed mechanism comprising a reciprocating member and a spring-pressed finger adjustably mounted on said member 90 and engageable with the signatures forming the inside of the book to advance them relative to the superimposed cover page so that it overlaps said inside signatures, a guard for said inside signatures adjacent said finger, and a support for spacing the depending portion of the cover out of the path of movement of said finger. 100

In testimony whereof, I affix my signature.

MARTIN CHRISTENSEN.
